WEB FEEDING MECHANISM FOR SCREEN PRINTING MACHINES

Hugo Fritz Worm, Uddevalla, Sweden, assignor to Aktiebolaget Teximpex, Uddevalla, Sweden, a corporation of Sweden

Application November 3, 1949, Serial No. 125,232
In Sweden October 3, 1947.

7 Claims. (Cl. 271—2.4)

1

The present invention relates to screen printing machines of the type, where a stencil of a certain length is placed on the material to be printed and the colouring matter is transferred to the material, whereafter the stencil is removed and the material is advanced a distance corresponding to the length of the stencil before the stencil is again placed on the material. By such a printing where the material, for instance a textile web, is moved step-wise over a printing table, it is very important that the length of the successive movements of the web is constant and equal to the length of the stencil, so that the stencil, which is guided in fixed guiding means, will always be placed in correct position relatively to the already printed pattern.

One object of the invention is to provide a device by means of which the step-wise movement of the web is automatically limited to the correct length and the invention is essentially characterized in that a roller for the feeding of the web is constructed and arranged to be driven through an overload coupling, and that there is provided a wheel connected to said roller by means of a disengaging clutch and preferably located on the roller shaft, the rotation of said wheel in at least one direction, corresponding to the feeding of the web, is limited by a fixed stop member cooperating with a movable stop member driven by said wheel.

In the accompanying drawings there is shown an embodiment of the invention applied to a textile printing machine. In the drawings Fig. 1 is an axial section through the device according to the invention; Fig. 2 is a side view of the device shown in Fig. 1; Fig. 3 is a section on the line 3—3 of Fig. 1; Fig. 4 is a section on the line 4—4 of Fig. 1; and Fig. 5 is a fragmentary elevation showing the operation of the shifting collar.

In the drawings 1 indicates a roller, which is driving an endless rubber web 2 on which the fabric to be printed is preferably secured by means of an adhesive so that it cannot slide relatively to the rubber web, which in turn does not slide on the roller 1 on account of the friction qualities of the rubber. The shaft 3 of the roller 1 projects outside one of its bearings 4 and on the projecting portion there is provided a chain wheel 5 for a driving chain from an electric motor (not shown). The chain wheel 5 is rotatably mounted on the hub 6 of a disk 7 secured to the shaft 3. To the hub 6 is secured another disk 8 on the opposite side of the chain wheel 5 and between the disks 7 and 8 and the sides of the chain wheel 5 there are provided friction rings 9, for instance from fibrous material, which rings are pressed against the wheel 5 so that at the turning of the wheel a limited torsional moment is transmitted to the shaft 3.

On the shaft 3 there is further rotatably

10 mounted a cog-wheel 10 which can be clutched to the shaft as will be described below and which cooperates with a toothed rack 11 sliding in guide members 12, 13. The rack 11 is at its one end provided with a stop ring 14 cooperating with the guide member 12 for limiting the movement of the rack in one direction. On the rack 11 there is further fastened a stop member 15 in the shape of a ring which cooperates with a face 16 on the fixed guide member 13. The stop member 15 is displaceable along the rack 11 and can be secured to it in different positions by means of a screw 17. On the rack there is also provided a scale 18 for indicating the displacement position of the stop member 15. In order to avoid play between the rack 11 and the cog-wheel 10 there is provided at the back of the rack a diagrammatically shown roller 19 which by a spring 20 is pressed against the rack 11 and in turn forces the rack against the wheel 10.

20 The cog-wheel 10 can be coupled to the shaft 3 by means of a coupling disk 21 secured to the shaft and provided with an axial flange 22. In the cylindrical ring formed by said flange is inserted a cylindrical projecting portion 23 of the wheel 10 having a smaller diameter than the inner diameter of the flange 22. In the ringshaped space between the flange and the wheel portion 23 is provided an elastic split ring 24 which can be expanded by means of a rotatable cam pin 25 between the ends of the ring and which is of oval or similar cross-section so that the pin in a certain rotating position permits the ring ends to approach each other and in another position separates the ring ends so that the ring is expanded. The pin 25 is provided with a cylindrical portion 26, which is journaled in an aperture in the wheel 10. Outside this aperture the pin portion 26 is secured to a lever 27 by means of which the pin 25 can be rotated. The swinging of the lever 27 is effected by means of a conical face 28 on a shifting collar 29 displaceable on the elongated hub of the wheel 10, which face 28 cooperates with the free end of the lever 27.

25 As shown in the drawing the shifting collar 29 is provided with a circular groove 30 for engagement with a clutch lever 30' by means of which the shifting collar 29 can be moved axially. Said lever may, if desired, be connected to the starting means of the driving motor for the roller 1 so that the motor is started when the friction clutch 22—24 is thrown in and stopped when the clutch is thrown out.

30 Finally, on the shaft 3 is secured a brake disk 31 with a brake strap 32 controlled by a hand lever 33 to temporarily hold the shaft 3 and the roller 1 in desired positions of rotation.

The device functions as follows:

35 During the printing operation the brake 31, 32 is tightened, the wheel 10 is disconnected from

the shaft 3 and the driving motor is at a standstill. At the same time the rack 11 is in its lower position where the stop ring 14 abuts against the guide member 12. When the fabric has to be advanced the motor is started and the clutch between the wheel 10 and the shaft 3 is thrown in. On account of the brake 31, 32, however, the shaft 3 is still standing still and the chain wheel 5 is rotating between the disks 7 and 8. When the brake is released the shaft 3 begins to rotate and the rack 11 is raised until the stop member 15 abuts against the face 16 on the guide member 13 when the rotation of the shaft is stopped while the chain wheel still rotates. After the brake 31, 32 has been tightened the motor can be stopped and the wheel 10 disconnected from the shaft 3, whereby the rack 11 sinks down to the initial position shown in the drawing.

It is evident that the maximum friction torque between the chain wheel 5 and the shaft 3 must be smaller than the maximum friction torque between the flange 22 and the wheel 10.

What I claim is:

1. A feeding mechanism for screen printing machines comprising a feeding roller for the material to be printed, a positively driven wheel, a driving connection comprising an overload coupling between said positively driven wheel and said roller, a rotatable wheel, a driving connection comprising a disengageable clutch between said roller and said rotatable wheel, a fixed stop member, a movable stop member driven by said rotatable wheel and cooperating with said fixed stop member in order to limit the rotation of said rotatable wheel in at least the direction corresponding to the feeding movement of the feeding roller.

2. A feeding mechanism for screen printing machines comprising a feeding roller for the material to be printed, a positively driven wheel, a driving connection comprising an overload coupling between said positively driven wheel and said roller, a rotatable wheel, a driving connection including a disengageable clutch between said roller and said rotatable wheel, a fixed stop member, a movable stop member driven by said rotatable wheel and cooperating with said fixed stop member in order to limit the rotation of said rotatable wheel in at least the direction corresponding to the feeding movement of the feeding roller, at least one of said stop members being adjustable to different positions for varying the feeding length of the material.

3. A feeding mechanism for screen printing machines comprising a feeding roller for the material to be printed, a positively driven wheel, a driving connection comprising an overload coupling between said positively driven wheel and said roller, a braking means for the roller located between said overload coupling and said roller, a rotatable wheel, a driving connection comprising a disengageable clutch between said roller and said rotatable wheel, a fixed stop member and a movable stop member driven by said rotatable wheel and cooperating with said fixed stop member in order to limit the rotation of said rotatable wheel in at least the direction corresponding to the feeding movement of the feeding roller.

4. A feeding mechanism for screen printing machines comprising a feeding roller for the material to be printed, a positively driven wheel, a driving connection comprising an overload coupling between said positively driven wheel and said roller, a rotatable cogwheel, a movable rack cooperating with said cogwheel, a driving con-

nection comprising a disengageable clutch between said roller and said rotatable cogwheel, a fixed stop member, a stop member secured to said movable rack and cooperating with said fixed stop member in order to limit the rotation of said rotatable cogwheel in at least the direction corresponding to the feeding movement of the feeding roller.

5. A feeding mechanism for screen printing machines comprising a feeding roller for the material to be printed, a positively driven wheel, a driving connection comprising an overload coupling between said positively driven wheel and said roller, a rotatable wheel, a driving connection comprising a disengageable clutch between said roller and said rotatable wheel, a fixed stop member and a movable stop member driven by said rotatable wheel and cooperating with said fixed stop member in order to limit the rotation of said rotatable wheel in at least the direction corresponding to the feeding movement of the feeding roller, said movable stop member automatically returning to its initial position when the rotatable wheel is disconnected from the roller.

6. A feeding mechanism for screen printing machines comprising a feeding roller for the material to be printed, a positively driven wheel, a driving connection comprising an overload coupling between said positively driven wheel and said roller, a rotatable wheel, a driving connection comprising a disengageable clutch between said roller and said rotatable wheel, a fixed stop member, a movable stop member driven by said rotatable wheel and cooperating with said fixed stop member in order to limit the rotation of said rotatable wheel in at least the direction corresponding to the feeding movement of the feeding roller, said overload coupling consisting of an overload friction clutch the maximum torque of which is such that it slips when the stop members come into contact with each other.

7. A feeding mechanism for screen printing machines comprising a feeding roller for the material to be printed, a positively driven wheel, a driving connection comprising an overload coupling between said positively driven wheel and said roller, a rotatable wheel, a driving connection comprising a disengageable clutch between said roller and said rotatable wheel, a fixed stop member, a movable stop member driven by said rotatable wheel and cooperating with said fixed stop member in order to limit the rotation of said rotatable wheel in at least the direction corresponding to the feeding movement of the feeding roller, said overload coupling consisting of an overload friction clutch the maximum torque of which is such that it slips when the stop members come into contact with each other and said disengageable clutch consisting of a friction clutch having a greater maximum torque than said overload friction clutch.
